METALS RECOVERY APPARATUS

Roy O. Gray, Denver, Colo., assignor of one-half
to C. F. Gillette, Denver, Colo.

Application March 28, 1942, Serial No. 436,663

8 Claims. (Cl. 209—184)

This invention relates to the separation and recovery of values from ores, and more particularly to the separation and recovery of metals susceptible of mercury amalgamation, and has for an object to provide improved means and apparatus wherethrough such separation and recovery may be efficiently accomplished.

Further objects of the invention are to provide: (a) improved means and apparatus for the separation and recovery of values from ores while dry; (b) improved means and apparatus operable to repetitiously expose the surfaces of value particles in a dry ore to intimate contact with mercury for the recovery of such particles through amalgamation; (c) improved means and apparatus operable to effect a traverse of dry ore particles through and for agitation within a mercury bath; (d) improved means for separating amalgamated values from associated gangue during traverse of the dry ore through a mercury bath; (e) improved means for rubbing and agitating ore particles during traverse of the dry ore through a mercury bath to facilitate amalgamation; (f) improved means and apparatus for the separation and recovery of values from dry ores which is simple and inexpensive of construction and operation, susceptible of practical development in the form of a compact, readily transportable unit, which is adapted for continuous, progressive operation, efficient in use, and which is arranged for complete operative actuation by means of a single power unit of relatively small size.

With these and other objects in view, all of which will more fully hereinafter appear, my invention comprises certain novel constructions, combinations and arrangements of parts, as will be hereinafter fully described and claimed, and as illustrated in the accompanying drawings, in which—

Figure 1 is a vertical section somewhat diagrammatic in character, taken longitudinally through an assembly of elements constituting one practical embodiment of the invention.

Figure 2 is a fragmentary detail section, on an enlarged scale, taken vertically through certain of the elements shown in the right hand and lower portion of Figure 1.

Figure 3 is a cross section taken on the indicated line 3—3 of Figure 2.

Figure 4 is a fragmentary, detail section taken substantially on the indicated line 4—4 of Figure 2.

Figure 5 is a cross section taken on the indicated line 5—5 of Figure 2.

Figure 6 is a fragmentary, detail section taken substantially on the indicated line 6—6 of Figure 2.

Figure 7 is a fragmentary, detail section, on an enlarged scale, taken substantially on the indicated line 7—7 of Figure 1.

Certain precious metals, particularly gold and silver, are found on occasion in earthy and siliceous deposits remote from supplies of water adequate for processing the deposits for the recovery of values by conventional placer methods. The values in such deposits are frequently in free milling form and hence available for recovery by amalgamation, particularly when the surface oxides inhibiting amalgamation are broken or rubbed away. The instant invention is primarily concerned with the provision of apparatus operable to successfully treat the material of such deposits, while in normal dry condition, for the recovery of values therefrom by means of amalgamation, and the apparatus of the invention is also operable to similarly treat and recover values from comminuted ores wherein the values sought are in a native, chemically uncombined state. As herein used, "ore" includes placer material, while "gangue" refers to that portion of such "ore" not sought to be recovered by operation of the present invention.

As shown in Figure 1, the improved apparatus includes an elongate box-like housing 10 supported at its lower end on a suitable frame or platform 11 and rising from and at an inclination with the support 11 to communicate at its upper end with the upper end of a somewhat similar elongate, box-like housing 12 whereof the lower end engages the support 11 at a point remote from the lower end of the housing 10. The housings 10 and 12 thus form an inverted V whereof the elements are securely and rigidly interconnected and secured to the support 11. A hopper 13 is carried by the lower end of the housing 10 and communicates in any suitable manner with the otherwise closed lower end of said housing, so that material fed into the hopper 13 is free to enter the lower portion of the associated housing.

A shaft 14 is mounted for rotation in and horizontally traverses the lower end of housing 10, and a shaft 15 is rotatably mounted in the junction of the housings 10 and 12 in spaced, parallel relation with the shaft 14, so that an endless conveyor 16, preferably of bucket type, may be engaged about suitable sprocket or roller elements 17 on the shafts 14 and 15 to mount said conveyor 16 for operation longitudinally of and within the

housing 10. It is the function of the conveyor 16 to transport material fed into the hopper 13 upwardly along and within the housing 10 and to deliver such material into the upper end of the housing 12 for travel downwardly within the latter housing under the influence of gravity. The conveyor 16 may be of any type or specific construction suitable to its purpose, the drawings illustrating a typical endless chain conveyor carrying spaced buckets arranged to scoop into the material fed through the hopper 13 and discharge such material as the buckets are inverted during their travel about the shaft 15.

A suitable power unit 18, such as an internal combustion engine, electric motor, or the like, is positioned on the support 11, preferably between the lower ends of housings 10 and 12, and is suitably and operatively connected, as by means of a belt 19 or equivalent power-transmitting means, with a pulley or comparable element fixed to an outer end of the shaft 14, so that actuation of the power unit 18 operates to rotate the shaft 14 and drive the conveyor 16.

The housing 12 is charged with a supply of mercury which fills the lower portion of said housing and rises therein to a level approximately indicated by the broken line 20, and the material delivered to said housing by the conveyor 16 descends through the upper portion of the housing 12 to engage against and rest upon the upper surface of the mercury body, a baffle 21, closing against side and top walls of the housing 12 and disposed with its lower margin spaced somewhat from the lower wall of said housing, serving to define a throat between the upper surface of the mercury body and the delivery end of the conveyor 16, through which the feed of ore material is restricted and regulated to the desired rate of flow.

Ore delivered to the upper surface of the mercury body will not, of itself, enter within and traverse the mercury, hence mechanical means are provided to positively carry the ore downwardly within and through the mercury, such means conveniently taking the form of an endless conveyor 22, of bucket type, mounted between and for travel about a lower shaft 23 mounted for rotation horizontally across a lower portion of the housing 12 and an upper shaft 24 mounted for rotation horizontally across said housing above the level of the body of mercury and in shielded relation with the baffle 21. The buckets 25 of the conveyor 22 open upwardly along the top flight of the conveyor and hence downwardly when travelling with the lower flight of the conveyor, and the conveyor is suitably driven so that the buckets on the lower flight of the conveyor pass through and become charged with ore resting on the surface of the mercury body and carry such ore downwardly through the mercury; a convenient means of so driving the conveyor, through the agency of the power unit 18, being illustrated as including a gear 26 fixedly carried by an outer end of the shaft 24 in meshing relation with a gear 27 fixed to the corresponding end of a jack-shaft 28, disposed for rotation in parallel relation with the shaft 24, and a belt or chain 29 operatively engaging about pulleys or sprockets fixed to corresponding ends of the shaft 15 and jack-shaft 28, so that rotation of the shaft 15 deriving from actuation of the conveyor 16 serves to rotate the shaft 24 in an opposite direction and hence drives the conveyor 22 in the direction desired.

When the conveyor 22 is actuated at slow to moderate speeds, the ore material engaged within the buckets 25 will, to some extent, leave said buckets during upward travel thereof along the upper flight of the conveyor, since the heavier mercury will tend to enter the buckets and displace the lighter ore material to rise through the mercury body. However, agitation of the ore material within the mercury and substantially complete clearing of the conveyor buckets of their charge of ore material is accomplished by directing a jet of mercury into the pockets of said buckets as they pass about the shaft 23 to start their upward travel. To provide the desired jet action, a suitable pump 30 may be positioned on the support 11 adjacent the power unit 18 and operatively connected with said power unit by means of a belt or equivalent drive, 31. The intake of the pump 30 is connected by means of a pipe or conduit 32, engaging through a wall of the housing 12, with the mercury body well above the lower end of the housing 12, and the outlet of the pump 30 is connected by means of a pipe or conduit 33 with a nozzle 34 engaging at an angle through a side wall of the housing 12 a short distance above the shaft 23 and directed to discharge into one side of each of the buckets as the latter pass about the shaft 23 to start their upward travel. To facilitate clearing of ore material from the buckets 25 under the action of the mercury jet delivered through the nozzle 34, said buckets may be formed with side walls converging from the mouth and toward each other adjacent the base of the bucket.

The surfaces of the value particles in the ore that escapes or is dislodged from the buckets 25 within the mercury body are brought into intimate contact with the mercury, so that the values sought, particularly gold and silver, may amalgamate with the mercury, and, because of the greater density of the amalgam it descends to the lower end of the mercury body whence the amalgam may be drawn off and recovered through a suitable discharge valve 35 on and communicating through the lowermost point of the housing 12. In certain cases, and particularly when the value particles sought to be recovered have oxidized surfaces, some of the values will fail of amalgamation within the housing 12 and will tend to rise with the lighter gangue to the surface of the mercury body. The material thus rising through the mercury will follow a substantially vertical path and hence may be diverted from the housing 12 through a throat formed by offset portions of the upper wall of the housing 12 and communicating with an agitating trap. The throat leading to the trap is preferably positioned well below the mercury level 20 and is formed by spacing the lower portion of the housing upper wall outwardly from the adjacent upper continuation of said wall, so that lighter ore material rising through the mercury body and impinging against the inner inclined surface of the housing upper wall lower section will move along such surface and pass through the throat into the trap.

The trap consists of an upwardly inclined, somewhat tortuous passage extending outwardly from the housing 12 to communicate between said housing and an open hopper 36 positioned with its discharge lip 37 slightly above the mercury level 20, so that the passage constituting the trap and a lower portion of the hopper 36 are charged 75 with mercury which rises in said hopper to the

same level as is maintained within the housing 12. The trap is defined by a substantially flat bottom wall 38 closing against the lower section of the upper surface of the housing 12 and inclining upwardly and outwardly therefrom to merge, through an offset 38', with the bottom of the hopper 36, side walls 39 rising from opposite margins of the wall 38 and continued to form side walls for the hopper 36, and a top wall 40 closing against the upper section of the upper conveyor wall and extending upwardly and outwardly therefrom in spaced relation above the wall 38 to terminate in an upwardly-directed flange 40' constituting an inner end wall of the hopper 36. The wall 40 of the trap is arranged as a series of upwardly-stepped sections which provide transverse shoulders 41 at intervals along its under surface, and a series of transverse baffles 42, each formed with an upturned lip 43, extending along the baffle margin remote from the housing 12, is disposed between the walls 38 and 40 in substantially parallel relation with the wall 38 and with their lips 43 spaced slightly below and inwardly toward the housing 12 from adjacent shoulders 41 of the top wall 40, so that a relatively narrow passage is defined between the wall 38 and the baffles 42, wherewith communication is had from the trap passage above said baffles through spaces left between adjacent margins of succeeding baffles. The innermost 30 of the baffles 42 is continued to form a wall 44 parallel with and spaced inwardly from upper and end walls of the housing lower section, and thus defines a flow passage along the conveyor lower section upper wall which opens adjacent the valve 35.

It is the function of the trap to agitate and rub the surfaces of the value particles engaged therein to facilitate amalgamation of said particles with the mercury within the trap. The gangue and associated value particles which enter the trap tend to rise through the mercury in the trap and impinge against the under surface of the wall 40, the upward and outward inclination of said wall directing the ore material toward the hopper 36, past the lips 43 of the baffles 42, and across the shoulders 41 of the wall 40, thus agitating and rubbing the ore material particles repeatedly during the transit of the material from the housing 12 to the hopper 36. The value particles having rubbed and freshly-exposed surfaces readily amalgamate, and the heavier, amalgamated material enters the flow passage along the trap wall 38 through the spaces between adjacent baffles and returns by gravity through such flow passage and its extension along the housing wall, to the lower portion of the housing 12 adjacent the valve 35, the lighter gangue and waste material, collecting above the mercury surface in the hopper 36 whence it may be discharged over the lip 37.

The platform or support 11 may, as is obvious, be mounted on wheels or skids for convenient transportation from one location to another, all of the elements and instrumentalities required for successful operation of the improved apparatus in the recovery of metallic values being carried by or associated with said support. The hopper 36 and the outer end of the trap assembly may be braced to the housing 12 or supported directly from the platform 11 by means of a frame or strut 45.

Since many changes, variations and modifications in the specific form, construction, and ar-

angement of elements shown and described may be had without departing from the spirit of my invention, I wish to be understood as being limited solely by the scope of the appended claims, 5 rather than by any details of the illustrative showing and foregoing description.

I claim:

1. In apparatus of the character described, a mercury body of substantial altitudinal extent, 10 a bucket chain for entraining ore material to the lower part of said body and a mercury jet directed against said buckets successively to force said ore material from said buckets.

2. In ore-treating apparatus, a pair of upwardly-converging, elongate housings intercommunicating at their upper ends, means for feeding finely divided ore material to the lower end of one of said housings, a body of mercury of substantial altitudinal extent in the lower portion of the other housing, means for elevating ore material from said feeding means through said first housing and to precipitate said ore material from the top of the first housing into the second housing and against the upper surface of the mercury body and bucket-conveyor means adapted to gather in buckets said ore material and mercury at said surface and entrain the same downwardly through the mercury body.

3. Apparatus of the character described, comprising a pair of upwardly-converging, elongate housings intercommunicating at their upper ends, conveyor means operable to elevate material within one of said housings for delivery within the upper end of the other housing, a charge of mercury filling the lower portion of and rising well within said other housing to receive the delivered ore on its upper surface, a bucket chain traversing said mercury charge and operable to entrain ore from the mercury surface and release said ore adjacent the lower end of the mercury charge, pump-actuated mercury jet means disposed to impinge against the buckets as they successively pass a predetermined low point within the mercury charge to clear ore material from said buckets and disperse and agitate the ore particles within the mercury charge.

4. Apparatus of the character described having ore receiving and elevating means, an upstanding, elongate housing inclined from the vertical and communicating at its upper end with said elevating means to receive ore therefrom, a charge of mercury of substantial altitudinal extent filling the lower portion of said housing, a baffle restricting the open area of said housing between the housing upper end and the mercury surface to control ore fed to said mercury surface, an endless conveyor of bucket type in the lower portion of said housing and extending above the mercury surface to entrain ore downwardly through the mercury, a pump-actuated mercury jet disposed to impinge within lower bucket elements of said conveyor and disperse and agitate ore material entrained by said buckets, a throat communicating through the upper, inclined wall of said housing within said mercury charge, an outwardly and upwardly inclined trap communicating with said throat, and a tortuous passage in said trap operable to agitate and rub ore material passing therethrough.

5. In apparatus of the character described having an upstanding, elongate housing inclined from the vertical and means for delivering finely

divided ore to the upper end of said housing, means for separating values from said ore, said means comprising a charge of mercury rising well within the lower portion of said housing to receive the ore against its upper surface, a bucket chain conveyor for entraining said ore downwardly through said mercury, pump-actuated mercury jet means disposed to clear ore material from the buckets of said conveyor adjacent the lower end of the housing.

6. A readily transportable metals recovery apparatus comprising a movable base carrying a pair of elongate housings upwardly converging and intercommunicating at their upper ends, one housing having ore receiving means at its lower end and means for conveying received ore to its upper end and for dumping the conveyed ore into the other housing, said other housing carrying therein a body of mercury adapted to receive on its upper surface said dumped ore, bucket-conveyor means adapted to gather in buckets said ore and mercury at said surface and entrain the same downwardly through the mercury and means for releasing the ore from the buckets near the bottom of the body and a

prime mover carried by said base for operating said conveying means, said entraining means and said releasing means.

7. In apparatus as defined in claim 6, said releasing means comprising a nozzle aimed at the interiors of said buckets as they successively pass the bottom point of said conveyor and means for projecting a jet of mercury from said nozzle into said buckets whereby to eject the contents of the buckets, successively, at a point near the lower extremity of their travel.

8. In apparatus for recovering metals from ores a housing carrying a body of mercury, means for depositing ore on the surface of said body, bucket chain conveyor means in said housing adapted to gather in said buckets said ore and mercury and carry such gathered material downwardly through said body and a nozzle aimed at the interiors of the buckets as they successively pass the bottom point of said conveyor and means for projecting a jet of mercury from said nozzle into the buckets whereby to eject the contents from the buckets at a point near the lower extremity of their travel.

ROY O. GRAY.
